J. D. KUHN

CAR DOOR HANGER

Filed May 20, 1926

Patented Oct. 16, 1928.

1,688,191

UNITED STATES PATENT OFFICE.

JOHN D. KUHN, OF LAWRENCE, KANSAS.

CAR-DOOR HANGER.

Application filed May 20, 1926. Serial No. 110,399.

My invention relates to door hangers and more particularly to car door hangers.

It is a purpose of my invention to provide means for supporting and guiding a door in its sliding movements toward and away from position in front of a door opening in a wall such as the side wall of a freight car, which means is so constructed that the same will prevent the disengagement of the door from the wall portion and which will provide for the ready sliding of the door due to the provision of anti-friction means in conjunction therewith.

It is a further purpose of my invention to provide means for guiding a door in its movements, comprising a bracket member or bracket members mounted on a wall portion which is exposed to the weather, that is provided with means for shedding water so that water will not come in contact with the runway with which the anti-friction means engages. The bracket members are preferably so constructed as to house the anti-friction means between themselves and the wall. The door member that is to be slidably engaged therewith is provided preferably with a bracket member or members having runways co-operating with the runways of the brackets mounted on the wall portion, the anti-friction means being mounted between said runways to facilitate the sliding movements of the door.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claim.

In the drawings:

Fig. 1 is a perspective view of a portion of a railway car, showing my improved door mounting means in position thereon.

Fig. 2 is a fragmentary section taken on the line 2—2 of Fig. 1.

Fig. 3 is a similar section taken on the line 3—3 of Fig. 1.

Fig. 4 is a perspective view, partly broken away, of the anti-friction bearing means employed, and

Fig. 5 is a transverse sectional view through

the bearing supporting means adjacent one of the bearing balls.

Referring in detail to the drawings:

My improved door mounting means comprises similar wall engaging bracket means 10 and 10', one of which is mounted on the wall portion and extends above the door opening 11 and the other of which is mounted on the wall portion and extends below the door opening 11. The bracket members 10 and 10' are substantially the same in construction and comprise a substantially vertically extending wall engaging portion 12 which is secured to the wall portion 13 by means of any suitable securing members such as bolts 14. Extending from the wall engaging portion 12 is an obliquely extending water shedding portion 15, and from said obliquely extending portion 15 extends a depending portion 16, the lower edge of which is inturned to form a runway 17, said runway forming portion 17 being shaped to provide a concave groove or runway in the upper surface thereof. The portions 16 and 17 thus form a rail portion co-operating with rail portions provided on the door 18 which is adapted to close the door opening 11 in the wall portion 13.

The door 18 is provided at its upper end with a bracket member 19 which has a vertically extending portion 20 engaging with the inner face of the door 18, the door being preferably provided with a slight offset, as indicated at 21, to receive said portion 20 so that the exposed face of the bracket 19 is flush with the exposed inner side of the door 18. The vertically extending portion 20 of the bracket 19 preferably extends upwardly beyond the upper edge of the door so as to overlap the vertically extending portions 16 of the bracket member 10 and is provided with an out-turned runway forming portion 22 which is curved so as to provide a concave runway facing the concave runway on the portion 17 and substantially aligning therewith when the door is assembled with the car in the manner shown in Fig. 2. The extreme outer end 23 of outturned portion 22 and the extreme inner end 24 of the inturned portion 17 are spaced respectively from the vertically extending portions 16 and 20 of the cooperating bracket members but serve as means to prevent disengagement of the door from the car body by any lateral movement of the bracket members relative to each other, the bracket member 19 being housed within the

bracket member 10 and confined by the same and the wall portion 13.

Mounted between the bracket members 10 and 19 is a ball retaining member 25 which is 5 preferably of channel shape and provided with a hook-like flange portion 26. The ball retaining member 25 is provided with openings through which the balls 27 project, the member 25 being provided with annular 10 flanges 28 surrounding the ball receiving openings, said flanges being inclined inwardly toward the openings to provide ball retaining seats in the member 25. The member 25 is mounted between the bracket members 15 10 and 19 with the balls 27 in engagement with the concave portions of the runways 17 and 22. The retaining member 25 is provided with end flanges 30 with which the bracket member 19 is adapted to engage to limit the 20 movement of the member 25 in either direction, thus preventing the ball retaining member from being carried out of the wall supported bracket 10 so as to become disengaged therefrom. The ball members 27 are thus 25 housed within the bracket member 10 and protected from the weather thereby. The door 18 may be provided with an angle member 31 having a portion 32 extending around the upper edge of the door to finish off the 30 same, and any suitable retaining means such as the rivets 33 may be provided for securing the bracket 19 and the angle member 31 in position on the door.

The lower wall engaging bracket 10' operates 35 with a lower bracket 34 carried by the door 18 at the lower end thereof, said bracket 34 having a vertically extending portion 35 secured to the outer face of the door 18 by any suitable securing means such as the 40 rivets 36 and depends therefrom. Said

bracket member 34 is further provided with a horizontally extending inturned portion 37 which is furthermore provided with an upturned portion 38 which terminates in an outturned runway forming portion 39, said 45 outturned portion being provided with a concave portion facing the concave portion 17 of the bracket member 10' and forming a co-operating runway portion therewith engaged by the balls 27 mounted in the ball retaining 50 member 25 which is the same in construction as the ball retaining member 25 mounted between the brackets 10 and 19. The bracket member 34 is thus confined between the wall portion 13 and the inner edge of the inturned 55 portion 17 in substantially the same manner as is the bracket member 19 by the bracket member 10. Furthermore the ball retaining member and the runways are protected from the rain because of the inclined water shedding portion 15, as in the case of the upper bracket member 10.

What I claim and desire to secure by Letters Patent is:

In combination with a door frame and door, a bracket including a wall portion attached to the lower portion of the door frame, extended downwardly and outwardly and terminating in an inwardly directed runway portion, a bracket including a portion attached to the lower portion of the door, having its lower edge inturned beneath the first named bracket and upturned adjacent the door frame and terminating in a runway portion 75 extended outwardly over the corresponding portion of the frame bracket, and a bearing member interposed between the runway portions of the respective brackets.

In testimony whereof I affix my signature.
JOHN D. KUHN.
